DESIGN FOR A FLOOR COVERING FOR BUSES OR THE LIKE

Samuel D. Moore, Cleveland Heights, and Theodore S. Rowe, Twin Lakes, Ohio, assignors to Sam Moore and Company, Cleveland, Ohio, a corporation of Ohio

Application August 4, 1943, Serial No. 110,836

Term of patent 14 years

To all whom it may concern:

Be it known that we, Samuel D. Moore and Theodore S. Rowe, citizens of the United States of America, residing at 2537 Taylor Road, Cleveland Heights, Cuyahoga County, State of Ohio, and Twin Lakes, Kent, Portage County, State of Ohio, respectively, having invented a new, original, and ornamental Design for a Floor Covering for Buses or the like, of which the following is a specification, reference being had to the accompanying drawings, forming part thereof.

In the drawings,

Fig. 1 is a top plan view of a floor covering for buses embodying our design; Fig. 2 is an enlarged, fragmentary perspective view thereof, with portions broken away for convenience of illustration, and Fig. 3 is a sectional view on lines 3—3 of Fig. 2 on a larger scale.

We claim:

The ornamental design for a floor covering for buses or the like, as shown.

SAMUEL D. MOORE.
THEODORE S. ROWE.
